UNITED STATES PATENT OFFICE.

THOMAS B. C. EVANS, OF HAWLEY, MINNESOTA.

CABINET.

Application filed May 6, 1922. Serial No. 558,995.

To all whom it may concern:

Be it known that I, THOMAS B. C. EVANS, a citizen of the United States, residing at Hawley, in the county of Clay and State of Minnesota, have invented new and useful Improvements in Cabinets, of which the following is a specification.

This invention relates to cabinets and has for its primary object, the provision of a cabinet primarily designed for use at automobile gasoline and oil stations, the cabinet being constructed to accommodate a large number of receptacles containing different grades of oil, any one of which receptacles can be conveniently removed from the cabinet when desired, while the cabinet is also designed to take care of any waste or spilt oil, the latter being conveyed to a suitable container from the bottom of the cabinet.

The nature and advantages of the invention will be better understood when the following detailed description is read in connection with the accompanying drawings, the invention residing in the construction, combination, and arrangement of parts as claimed.

In the drawings forming part of this application, like numerals of reference indicate similar parts in the several views, and wherein:

Figure 1 is a view in elevation of the cabinet constructed in accordance with the invention.

Figure 2 is a view, showing the cabinet in vertical section.

Figure 3 is a plan view of one of the shelves designed to support the oil container.

Figure 4 is a plan view of the support for said shelf and designed to constitute a tray.

Figure 5 is a sectional view taken on line 5-5 of Figure 1.

Referring to the drawings in detail, 10 indicates a cabinet which may be constructed from any suitable material and vary in size and cross sectional configuration without departing from the spirit of the invention. The cabinet is however preferably of cylindrical formation in cross section, and provided with a door 11, so that access may be readily had to the cabinet when desired. Arranged within the cabinet is a standard

be hereinafter specifically described, and this standard passes through suitable bearings 13 forming part of brackets 14 which are terminally secured to the cabinet as shown. The standard 12 is journaled in a roller bearing 15 at the top of the cabinet, while at the lower end of the latter is the standard journaled in ball bearings 17. The standard terminates an appreciable distance above the bottom of the cabinet, and reposing upon the bottom of the cabinet is a receptacle 18 which is adapted to receive the oil which may possibly be spilled within the cabinet, and this oil is conveyed to the receptacle in a manner to be hereinafter described.

Supported by the standard 12 is a plurality of spaced super-imposed shelves, each shelf being in the form of a disk and indicated at 19, while the disk 19 reposes upon a support of similar configuration and which support is indicated at 20. The shelf proper is provided with a circumferential series of openings 21 of a size to accommodate containers 22, and it is obvious that each shelf can thereby support a plurality of such containers 22, so that different grades and qualities of oil can be kept within the cabinet. Each container 22 reposes upon the support 20, and this support 20 is formed to provide a plurality of radially disposed corrugations 23, the corresponding inner extremities of said corrugations communicating, or leading into the standard 12. It is of course to be understood that the standard 12 is hollow, so that any waste or spilled oil will be conveyed through the corrugations to the standard 12, passing through the latter to the receptacle 18 above referred to. While the cabinet may be used in any particular place, it is primarily intended to have this cabinet arranged at the curb adjacent the gasoline tank, so that oil can be dispensed with the same convenience that gasoline is now dispensed with, it being only necessary to open the door of the cabinet and turn the standard together with the shelf in order to bring the proper container 22 within reach of the user.

While it is believed that from the foregoing description, the nature and advantages of the invention will be readily apparent, I desire to have it understood that I do not limit myself to what is herein shown and

described, and that such changes may be resorted to when desired as fall within the scope of what is claimed.

What I claim is:—

5 A cabinet of the character described comprising a cabinet body, a vertical hollow shaft journalled within the body and arranged centrally thereof, annular supports including a bottom and vertical wall, said supports being mounted upon the shaft in 10 spaced superimposed relation, a shelf ar-

ranged in each support and also mounted on said shaft, each shelf having a circumferential series of openings to accommodate receptacles as described, the bottom of each 15 support being formed with radially disposed channels, and said hollow shaft having openings therein immediately above each channel of the adjacent support for the purpose specified.

In testimony whereof I affix my signature.

THOMAS B. C. EVANS.
